UNITED STATES PATENT OFFICE.

JOHN B. BURDETT, OF CHICAGO, ILLINOIS, ASSIGNOR TO BURDETT MANUFACTURING COMPANY, OF CHICAGO, ILLINOIS, A CORPORATION OF ILLINOIS.

ELECTROLYTIC CELL FOR GENERATING HYDROGEN AND OXYGEN GASES.

1,086,804.

Specification of Letters Patent.

Patented Feb. 10, 1914.

Application filed October 28, 1913. Serial No. 797,734.

To all whom it may concern:

Be it known that I, JOHN B. BURDETT, a citizen of the United States, residing at Chicago, in the county of Cook and State of Illinois, have invented certain new and useful Improvements in Electrolytic Cells for Generating Hydrogen and Oxygen Gases, of which the following is a specification.

This invention relates to apparatus for the electrolytic production of hydrogen and oxygen gases, and has for its object the construction of a cell that is simple and reliable in its operation, and renders possible the economical production of these gases of a high percentage purity.

In the accompanying drawings: Figure 1 is a section of Fig. 2, on the line A—A; Fig. 2 is a plan of the cell, showing one side removed; Fig. 3 is a top plan of the upper part of the electrode-element and upper edge of outer cell; Fig. 4 is a view of the compartment casting on the line B—B, Fig. 1, showing the gas-collecting channels and the diaphragm; and Fig. 5 is a view showing the method of securing the diaphragm to the casting.

In Fig. 1, within a cell 11, made of suitable material, is the electrode-element 12, consisting of a casting 13, to which are attached ends 14 (Fig. 2) and sides 15. The element is suitably supported with its open end downward within the cell upon insulators *d*. The casting 13, as shown in Figs. 1, 2 and 4, consists of a box-like structure subdivided into a number of compartments by the partitions 16; these compartments are shown parallel to each other, extending from end to end of the casting 13, alternate ones communicating with each other through the openings 17, 18 (see Fig. 3) communicating with channels or conduits 19 and 20 on the top of casting 13, the openings and channels serving as a means for the gas generated to pass out of the cell. Secured to the edges 45 of the partitions 16 is a diaphragm 21, of asbestos or other suitable material, which extends to the bottom level 22 of the element 12. The diaphragm is attached to the partitions 16 by suitable clamps 22, and bolts 50 23, (see Fig. 5) the clamps 22 extending the full length of the partitions to insure a tight joint. At alternate ends, the partitions 16 are notched a short distance, shown at 24 in Figs. 4 and 5, to permit the upper edge of 55 the diaphragm to pass into the next com-

partment. The diaphragm is folded back and forth in a tortuous form, as shown in Fig. 4, on the successive partitions, throughout the entire casting, and having its ends folded back against the end of the compartment, as shown at 30, forming a tightly closed chamber, thereby providing a continuous, unbroken, diaphragm in the cell, and providing a plurality of chambers, 62, 63, extensions of the compartments in the casting 13 formed by partitions 16, and constituting the cathode and anode compartments of the cell in which are placed the electrodes 35, 36. At each folded end of the diaphragm, the folds are secured in place 70 and rigidly held in a vertical position by the plates 25 which are bolted or otherwise secured, as at 26, and extend down to the lower edge of the diaphragm. The ends 14 of the element are secured by bolts 27 to the casting 13, and to the angle iron 28 (the latter shown in Fig. 1, and indicated in dotted lines in Fig. 2). The sides 15 are secured by the bolts 29 to the casting 13, and to the angle iron 28, all joints being made tight 80 with suitable packing.

From the top of the casting 13, extending into each compartment, are the electrode supports 31, two in each compartment, and suitably insulated at 32 and 33 from the casting. The electrode supports are secured, preferably by welding, as at 34, to the electrodes 35, 36, which latter extend vertically down between the vertical folds of the diaphragm 21 and are held parallel at the bottom by the cross-pieces 37. The supports 31 are electrically connected to bus-bars 41, 42, through rods 38 which pass through tubes 39, the latter having an insulating lining 40.

The electrodes 35, 36, are preferably of 95 sheet iron, or sheet steel; the oxygen electrodes and their supports 31 are coated as by electroplating, or otherwise, with another suitable metal.

Each end, 14, of the electrode-element contains a plurality of conduits 43, 44, shown in Fig. 2. The conduits 43 communicate at their upper ends with alternate compartments in which is generated one of the gases, while the conduits 44 communicate with the 105 remaining intermediate compartments in which is generated the other gas; the lower ends of each conduit communicate with the electrolyte in the outer cell. The upper ends 110 of these conduits are always below the level

64 of the electrolyte within the inner electrode compartments, and are of such length as to prevent any escape of gas.

Each of the gas-channels 19, 20, Fig. 3 is provided with a safety-outlet, 45, shown in Fig. 1, which extends down into the outer electrolyte below the normal level of that within the compartments. Should the gas-pressure within a compartment suddenly increase for any reason, the excess will escape through the safety outlet 45 into the atmosphere before it could filter through the diaphragm into the next compartment. This safety outlet may be fixed, for constant gas pressure, or may be movable about the joint 46, to place the outlet in an inclined position with its opening at a variable depth, thereby adjusting the outlet to different pressures at which it is desired the cell shall operate.

Connected to the gas-channels are upright tubes 47, 48, which communicate with the lanterns or wash-bottles, 49, 50. Within each lantern is a bell, 51, suspended from the top, surrounding, but spaced from, the prolonged tubes 47, 48. The lanterns are filled with water to the level shown; gas passing through tubes 47 and 48 flow down through the space 52 between the bell and tube, passes out below the bell, through the water, and out through tubes 53, 54. Within the bell 51, and extending down through the lanterns, and the tubes 47, 48, is an inner safety-tube, 55, reaching below the surface 35 of the electrolyte in the electrode element. This tube opens at 56 into the space in the lanterns which permits filling the lanterns to a constant level with distilled water by opening the top 58, or otherwise, any excess 40 of water flowing down the safety-tube into the electrolyte. This safety-tube serves a further purpose in that in case of excessive pressure in the gas-main, either continuous or instantaneous, or of a reduction of pressure 45 sure in the interior of the cell, the pressures in the interior of the cell and in the gas-main are brought to a balance, thereby preventing the siphoning out of the water in the lanterns.

Distilled water is supplied to the cell, to replace that consumed by electrolysis, through the feed-tube 59, which has outlets into each compartment, at 60. This tube may be simply placed in the cell, as shown, 55 or may enter one of the sides, or bottom, of the tank, and deliver water to each compartment. By supplying water uniformly in this manner to each compartment, the electrolyte in all the compartments is maintained at a uniform gravity, and the operation of the cell is rendered more constant. The water issuing in jets from openings 60 also tends to circulate the electrolyte in the anode and cathode compartments, the electrolyte entering at the bottom, and flowing

out through the channels 43, 44. The electrolyte 61 in the outer cell is covered with a layer of paraffin oil, or other suitable material, to prevent the absorption of carbon dioxide from the atmosphere.

During the operation of the cell, the evolution of gas at the electrodes causes a circulation of the electrolyte within the compartments, the electrolyte entering at the bottom of the electrode-element, passing upward along the surface of the electrodes and diaphragm, and out into the outer cell through the channels 43, 44. This automatic circulation washes the electrodes and diaphragm free from gas bubbles, thereby reducing the internal resistance of the cell, and further insures uniformity in density of the electrolyte at all parts of the cell. The liberated gas passes out from the several compartments through their respective 85 openings 17, 18, into the channels or conduits 19, 20, and through the lanterns or wash-bottles 49, 50. The evolution of gas on the electrodes causes a further circulation of the electrolyte within the compartment, upward along the surface of the electrode, down between the two, and under the bottom and upward again between the electrode and diaphragm, thereby maintaining uniformity of density within the compartment. 90

I claim:—

1. In an electrolytic cell for generating hydrogen and oxygen, electrode compartments, gas-conduits communicating with said compartments, a safety-outlet to control the gas pressure in said gas-conduits, and means to automatically circulate electrolyte between said compartments and outer cell.

2. In an electrolytic cell for generating hydrogen and oxygen, an electrode-element comprising a casing having partitions forming gas-tight compartments, electrodes supported by said casing, gas-conduits communicating with said compartments, and an adjustable conduit communicating with a gas-conduit and projecting into the electrolyte to predetermine the pressure of an evolved gas.

3. In an electrolytic cell for generating hydrogen and oxygen, an electrode-element comprising a subdivided casing, extensions to said subdivisions, said extensions constituting cathode and anode compartments having open bottoms, and means to supply jets of fresh electrolyte to said extensions.

4. In an electrolytic cell for generating hydrogen and oxygen, a plurality of cathode and anode compartments, a continuous unbroken diaphragm so mounted as to constitute separating walls for said compartments, and means to hold said diaphragm in place.

5. In an electrolytic cell for generating

- hydrogen and oxygen, an electrode-element comprising a casing having partitions forming gas-tight compartments, a diaphragm attached to said partitions and so mounted as to form extensions to the gas-tight compartments, said extensions constituting cathode and anode compartments, and means to automatically circulate the electrolyte between said compartments and the outer electrolytic cell.
6. In an electrolytic cell for generating hydrogen and oxygen, an electrode-element comprising a casing subdivided into compartments by partitions, a continuous diaphragm supported by said partitions and folded back and forth on successive partitions, side-plates and end-plates supported by said casing and coöperating with said diaphragm to form a plurality of chambers, said chambers being extensions of said compartments, and constituting cathode and anode compartments, and means to hold said diaphragm rigid.
7. In an electrolytic cell for generating hydrogen and oxygen, an electrode-element comprising a casing subdivided into gas-tight compartments by partitions, a diaphragm supported by said partitions and forming extensions to said compartments, said extensions constituting cathode and anode compartments, electrodes supported by said casing within said extensions, gas-collecting spaces within said compartments above said electrodes, and a passage to deliver liberated gas to a gas-conduit.
8. In an electrolytic cell for generating hydrogen and oxygen, an electrode element subdivided into cathode and anode compartments, a diaphragm normally submerged between said compartments, electrodes in close proximity to and parallel with said diaphragm, and means preventing the diaphragm from becoming uncovered.
9. In an electrolytic cell for generating hydrogen and oxygen, an outer cell arranged to hold an electrolyte, an inner electrode element open at the bottom and supported above the bottom of said cell, a space at the top of said electrode element for the collection of gases, a conduit between said space and the outer electrolyte, and a channel communicating between the inner electrode element and a point at a lower level in the outer cell.
10. In an electrolytic cell for generating hydrogen and oxygen, an outer cell arranged to hold an electrolyte, an electrode element immersed in said electrolyte, passages communicating with said electrolyte at one level, and with the interior of said electrode element at a higher level.
11. In an electrolytic cell for generating hydrogen and oxygen, an outer cell arranged to contain an electrolyte, an electrode-element comprising a plurality of cathode and anode compartments within said outer cell, and means to automatically circulate the electrolyte between the outer cell and said compartments.
12. In an electrolytic cell for generating hydrogen and oxygen, electrodes and supports therefor, said electrodes united to said supports by welding.
13. In an electrolytic cell for generating hydrogen and oxygen, electrodes and supports therefor, two electrodes united to one set of supports and maintained parallel by distance pieces at another point in said electrodes.
14. In an electrolytic cell for generating hydrogen and oxygen, electrodes for generating gases, means for conveying said gases from the cell to a wash-bottle and then to an outer gas-main, and means to prevent the siphoning of the solution in the wash-bottle into the electrolytic cell.
15. In an electrolytic cell for generating hydrogen and oxygen, an outer cell, an inner electrode-element, means for generating gases within said electrode element, means to convey said gases through a wash-bottle to an outer gas-main, and means to establish a uniform pressure between the outer gas-main and the interior of the electrode-element.
16. In an electrolytic cell for generating hydrogen and oxygen, an electrode-element consisting of a plurality of compartments closed at the top, said compartments constituting cathode and anode chambers, said cathode chambers communicating with a gas-conduit and wash-bottle, said anode chambers communicating with a separate gas-conduit and wash-bottle, safety-tubes attached to said gas-conduits to control the gas-pressure therein, and means to supply fresh electrolyte to said cathode and anode compartments.
17. In an electrolytic cell for generating hydrogen and oxygen, the combination of cathode and anode compartments separated by a wall or walls made of impervious and pervious parts, the impervious walls forming a gas-collecting chamber, the pervious parts normally submerged in an electrolyte, means to circulate said electrolyte, means to supply fresh electrolyte to said compartments, means to convey away evolved gases through wash-bottles to outer gas-mains, means to prevent the uncovering of the pervious part of the wall or walls, and means to establish a direct connection between the electrolyte in said compartments and the outer gas-mains.
18. In an electrolytic cell for generating hydrogen and oxygen, cathode and anode compartments, and means to supply a jet of electrolyte to each compartment at the bottom.
19. In an electrolytic cell for generating hydrogen and oxygen, an outer cell arranged

to contain an electrolyte, an electrode-element comprising a plurality of cathode and anode compartments within said outer cell, means to supply electrolyte separately to each compartment at the bottom, and means to automatically circulate the electrolyte between the outer cell and said compartments.

In testimony whereof I affix my signature in presence of two witnesses.

JOHN B. BURDETT.
